UNITED STATES PATENT OFFICE.

JACOB KERSTEN, OF GRAND RAPIDS, MICHIGAN.

ADJUSTABLE DRESS-FORM.

1,287,043.

Specification of Letters Patent. Patented Dec. 10, 1918.

Application filed August 7, 1917. Serial No. 184,816.

To all whom it may concern:

Be it known that I, JACOB KERSTEN, a citizen of the United States of America, residing at Grand Rapids, in the county of Kent 5 and State of Michigan, have invented certain new and useful Improvements in Adjustable Dress-Forms; and I do hereby declare the following to be a full, clear, and exact description of the invention, such as 10 will enable others skilled in the art to which it appertains to make and use the same.

This invention relates to an adjustable dress form. It is a primary object and purpose of the present invention to construct a 15 dress form of a plurality of sections, connecting them with adjacent sections in such manner that each section may be readily adjusted with respect to said adjacent sections, and to support the dress form as a whole on 20 a vertical standard coupled with which is an upper extension rod loosely mounted on and universally adjustable with respect to the relatively stationary standard, whereby in conjunction with the adjustment of the 25 sections with respect to each other, the form may be made to take a variety of positions and shapes not possible with dress forms heretofore used. A further object of the invention consists in the provision of an 30 extension rod to the supporting standard which is not only universally adjustable angularly, but which also has a limited vertical adjustment with respect thereto, this giving the form further and easier range 35 of adjustment. A still further feature of the invention consists in novel means for yieldingly mounting the dress form as a whole upon its supporting standard, whereby the form has a large range of adjustment 40 in the length thereof, yet at the same time, is yieldingly held against too free or aimless movement of the form with respect to the supporting standard. Many other features of novelty and utility will appear as 45 understanding of the invention is had from a consideration of a preferred form thereof shown in the accompanying drawings, in which,

Figure 1 is a vertical section through a 50 dress form embodying my invention and showing the form sections in normal position.

Fig. 2 is a similar sectional view showing the form adjusted to a different position 55 from that shown in Fig. 1.

Fig. 3 is an enlarged vertical section

through the upper end of the supporting standard and illustrating the universal adjustable and vertical connection of the extension rod thereto.

60

Fig. 4 is a front elevation of the form, with parts broken away, illustrating a still further capability of adjustment of the form.

Fig. 5 is a perspective view enlarged, 65 showing the specific means of adjustable connection between adjacent sections of the form, and

Fig. 6 is a view similar to Fig. 4 showing 70 an additional capability of adjustment of the form due to my invention.

Like reference characters refer to like parts in the several views of the drawings.

In construction, a base 1 is provided projecting upwardly from which is a rod 2 telescoping into the lower end of a hollow tubular standard 3. A collar 4 is secured to the lower end of the standard 3 serving as a support for the lower end of a coil spring 5, against the upper end of which a spider 6, 80 having a plurality of radially projecting slotted arms 7, bears. To each arm 7 a base section 8 of the form is adjustably connected by bolt and wing nut construction, as indicated at 9, all of which being well known in 85 the dress form art, is not shown and described in any measure in detail. It is also understood that the standard 3 may be vertically adjustable on the rod 2 and may be held in any position to which it may be adjusted, this however, forming no part of the 90 present invention and not being shown or described.

The form is comprised of a plurality of sections 10. In practice, the form is divided 95 substantially horizontal at the hip and bust portions thereof, whereby, upper, lower, and intermediate groups of sections are provided, these being connected by adjustable connecting devices which permit vertical adjustment of the sections of any group with respect to the sections of the adjacent group, while the sections of a group are similarly connected together by adjustable connecting devices which permit a horizontal adjustment of said sections of a group with respect to the adjacent sections of the same group. This adjustable connecting means 100 comprises an elongated strip of sheet metal 11, rigidly secured at one end to a section, and then bent, as indicated at 12, so that the strip of metal is spaced a slight distance 105 110

from the adjacent section over which it extends. Strip 11 has an elongated slot 13 cut therein and on the section over which it extends, a plate 14 is permanently secured 5 transversely of said strip 11. A threaded bolt or stud 15 projects from between the ends of the plate 14 through the slot 13. A washer 16 is placed over the bolt upon which a short coil spring 17 is located, and then a 10 combined housing cap and wing nut is threaded on to the end of the bolt. The housing cap and wing nut is formed from sheet metal and includes a domelike housing 18, into which an end of the spring 17 enters, 15 and two oppositely extending arms 19 which terminate in ears 20 bent at right angles to the plane of the arms 19. The metal at the middle of the dome is cut away to pass the bolt and is threaded to receive the same, 20 it being apparent that with this construction a yielding adjustable connection of the sections to each other is provided, and one in which the spring is substantially housed and concealed, while with such construction the 25 adjustment and proper tension of the spring is very easily secured, the lower edges of the dome 18 and the distance thereof from the plate 11, serving as a gage which one familiar with assembling devices of this 30 character may follow to determine the proper position of the combined housing and wing nut on the threaded stud.

The standard 3 extends slightly above the intermediate group of sections of the form, 35 In its upper end a hollow sleeve 21 is inserted, it being provided at its upper end with a head 22 which comes against the upper end of the standard 3. The sleeve is secured in place by a bolt 23 passing through 40 both the standard and sleeve adjacent the lower end of the sleeve. In practice it may be advisable to rivet over the end of the bolt 23 instead of using a removable nut. An extension rod 24 is provided at its lower end 45 with outwardly struck rounded ears 25, said rod passing upwardly through the upper end of the sleeve, the ears forming a stop to prevent disengagement therefrom. It is apparent that the rod may move vertically 50 in sleeve 21 between the upper end thereof and the bolt 23, having such range of vertical adjustment. The upper end of the rod 24 is threaded and receives lower and upper nuts 26 and 27, between which slotted plates 55 28 are located, these connecting to the upper neck portions of the upper sections 10. By tightening the upper nut 27, the plates 28 may be held against movement as is obvious.

With a construction of the character described, practically any adjustment desired of the form may be had. In Fig. 1 is shown a substantially normal configuration. In Fig. 2, by reason of the adjustability of the extension rod 24, the form may be adjusted 65 so as to indicate an abnormally large bust,

and at the same time if desired, the intermediate group of sections of the form may be adjusted to bring the upper edges of the rear sections of said group closely adjacent the supporting standard 3, as well as an adjustment of the lower sections of the form for an enlargement of the hip portions thereof. In Fig. 4 there is indicated an adjustment for one side of the hip portion of the form to indicate an enlargement thereof, 70 while in Fig. 6 there is indicated an abnormally high shoulder. It will also be obvious that on longitudinal adjustment of the form so that the lower end of the rod 24 comes into contact with the head 22 at the upper 75 end of the sleeve 21, a still further longitudinal adjustment of the form may be attained by merely compressing the spring 5, and at all times this spring serves to support and hold the form in upper position on the 80 standard and yielding resists too free movement thereof around the standard. In fact, with my construction an absolutely complete and universal adjustability of the form is attained, making it practically possible to conform the same to any and all 85 deformities of the human figure. While I have not shown in the drawings, the rod 24 tilted forward or opposite to the position which is shown in Fig. 2, nevertheless, it is 90 obvious that this can be done, and the form made to simulate a figure having a flat chest. The extension rod 24 is universally adjustable to any angle with respect to the standard 3 and in conjunction with the adjustment of the sections with respect to each other, practically any and all shapes of 95 figures may be simulated.

I claim:

1. In a dress form, the combination with 105 a plurality of independently adjustable form sections, of a vertical supporting standard extending through the form to a point below the upper ends of the uppermost of said sections, an extension rod loosely inserted into 110 the upper end of said standard, and universally angularly adjustable about the axis of said standard and also adjustable lengthwise thereof, means limiting the range of longitudinal adjustment of said rod in the 115 standard, and means connecting said rod adjacent its upper end to the upper parts of said uppermost sections.

2. In a dress form, the combination with 120 a plurality of independently adjustable form sections, of a vertical supporting standard extending through the form to a point below the upper ends of the uppermost of said sections, an extension rod loosely inserted into 125 the upper end of said standard, a stop located below the upper end of and within the standard to limit the entrance of said rod into the standard, means preventing disconnection of the rod from the standard and providing a socket for the end of the rod 130

- permitting universal angular adjustment of the rod about the axis of the standard, and means connecting said rod adjacent its upper end to the upper parts of said uppermost sections.
3. In a dress form, the combination with a plurality of independently adjustable form sections, of a vertical tubular supporting standard extending through the form to a point below the upper ends of the uppermost of said sections, a sleeve having an enlarged head inserted into the upper end of the standard, said head having an opening therethrough, a bolt passed through the standard and sleeve a distance below the upper end of the standard, a rod extending loosely through the opening in said head above said sleeve, said rod at its lower end being formed with means preventing disengagement thereof from the sleeve and allowing universal angular adjustment of the rod about the axis of the standard, and means connecting said rod adjacent its upper end to the upper portions of said uppermost sections.
- 25 4. In a dress form, the combination with a plurality of independently adjustable dress form sections, of a vertical supporting standard extending through the form to a point below the upper ends of the uppermost of said sections, a rod loosely connected at its lower end to and at the upper end of the standard and mounted for universal adjustment about the axis of the standard, means connecting said rod adjacent its upper end to the upper portions of said uppermost sections, a base mounted loosely around said standard and connected to the lowermost sections of the form, and yielding means on the standard on which the base rests, substantially as described.
5. In a dress form, the combination with a plurality of independently adjustable form sections, of a vertical support extending through the form, a universal joint in said support at a point below the upper ends of the uppermost of said sections, whereby the upper part of said support is universally angularly adjustable about the vertical axis of the lower part of said support, and means connecting the upper end of the support with the uppermost sections.
- 10 6. In a dress form, the combination with a plurality of independently adjustable form sections, a vertical support extending through the standard and connected at its upper end to the uppermost of said sections, said support comprising an upper section adjustable longitudinally with respect to a lower relatively fixed section, and a universal joint in said support whereby said upper section and attached form sections are universally angularly adjustable about the vertical axis of the lower section.
- 15 7. In a dress form, the combination with a plurality of sections, of slotted metal strips secured to certain sections and extending over adjacent sections, a flat metal bar secured to each of said adjacent sections at each end thereof and located under and transversely of the length of said slotted strips, a screw secured to each of said bars between the ends thereof and between the connections of said bars to the sections, said screw extending through the slot of the adjacent strip, and means threaded onto the screw for binding the strip against the bar, substantially as described.
- 20 8. In a dress form, the combination with a plurality of independently adjustable form sections, of a vertical supporting standard extending through the form to a point below the upper ends of the uppermost of said sections, a rod loosely connected at its lower end to and at the upper end of the standard and mounted for universal adjustment about the axis of the standard, means connecting said rod adjacent its upper end to the upper portions of said uppermost sections, a base mounted loosely around said standard and connected to the lowermost sections of the form, and yielding means on the standard on which the base rests, substantially as described.
- 25 9. In a dress form, the combination with a plurality of independently adjustable form sections, of a vertical support extending through the form, a universal joint in said support at a point below the upper ends of the uppermost of said sections, whereby the upper part of said support is universally angularly adjustable about the vertical axis of the lower part of said support, and means connecting the upper end of the support with the uppermost sections.
- 30 10. In a dress form, the combination with a plurality of independently adjustable form sections, of a vertical support extending through the form, a universal joint in said support at a point below the upper ends of the uppermost of said sections, whereby the upper part of said support is universally angularly adjustable about the vertical axis of the lower part of said support, and means connecting the upper end of the support with the uppermost sections.
- 35 11. In a dress form, the combination with a plurality of independently adjustable form sections, of a vertical support extending through the form, a universal joint in said support at a point below the upper ends of the uppermost of said sections, whereby the upper part of said support is universally angularly adjustable about the vertical axis of the lower part of said support, and means connecting the upper end of the support with the uppermost sections.
- 40 12. In a dress form, the combination with a plurality of independently adjustable form sections, of a vertical support extending through the form, a universal joint in said support at a point below the upper ends of the uppermost of said sections, whereby the upper part of said support is universally angularly adjustable about the vertical axis of the lower part of said support, and means connecting the upper end of the support with the uppermost sections.

Copies of this patent may be obtained for five cents each, by addressing the "Commissioner of Patents, Washington, D. C."

JACOB KERSTEN.

In testimony whereof I affix my signature.
